CREEL

Burt A. Peterson, Rockford, Ill., assignor to Barber-Colman Company, Rockford, Ill., a corporation of Illinois

Application December 19, 1931, Serial No. 582,003

15 Claims. (Cl. 242—131)

This invention relates to creels for supporting yarn masses which are to be unwound and is in the nature of an improvement upon the creel disclosed in my application Serial No. 283,244, filed June 6, 1928 (now Patent No. 1,872,179), issued August 16, 1932. The particular object of the invention is to reduce the time required to withdraw a set of yarn-mass carriers which have been substantially or wholly emptied and to place in running position a set of full yarn-mass carriers.

In the accompanying drawings:

Figure 1 is a plan view of a warping apparatus comprising a creel that embodies the features of my invention.

Fig. 2 is a fragmental side elevation of the creel.

Fig. 3 is a fragmental plan view of the creel. Fig. 4 is a fragmental elevation.

Referring to Fig. 1: A denotes a warper which may be of any preferred character and B is a creel embodying the features of my invention. While the creel may be of various forms, I have herein shown it as comprising two upright frames 1 and 2 which are adjacent each other at the end near the warper and separated from each other at the opposite end so as to form a V-shaped structure. Each frame comprises means for supporting and moving an endless series of yarn-mass carriers.

Referring now to Figs. 3 and 4: 3 denotes an upright bar to one side of which is attached a column or vertical series of yarn-mass supports 4. These supports may be of any desired nature appropriate to the character of the yarn masses to be supported. In the present drawings, I have shown cross-wound yarn masses or cheeses a formed upon cores b, the bar 3 being provided with devices 5 which non-rotatably support the cores with their axes in horizontal position. Surrounding each yarn mass a is a cylindrical casing 6 having a closed end 7 which is rigidly secured to the bar 3, the opposite end of the casing being open for the insertion of full cheeses and the removal of cheese cores. The casings 6 enable the ballooning yarn to set up air currents that blow the lint out toward the front of the creel and thus prevent lint from accumulating on the yarn masses. The casings also serve to keep the ballooning threads out of contact with one another. As shown in Fig. 2, the yarn-mass supports 5 and the casings 6 on one bar 3 are staggered with relation to the supports and casings on the adjacent bars, so as to economize space.

Attached to the upper end of the bar 3 is a roller 8 which is arranged to run upon a track

member 9 that is secured in the upper portion of the creel frame. Said roller is located at the outer side of the bar 3.

The bars 3 are secured together to form an endless series by means of two flexible elements 10 and 11 secured to the inner sides of said bars near the upper and lower ends thereof. Each chain extends around sprocket wheels 12, 13 and 14 mounted in the creel framework for rotation upon vertical axes. The two driving sprocket wheels 12 are fixed upon a shaft 12^a, the sprocket wheels 13 and 14 being idlers. The lower chain 11 is arranged to run along guide flanges 15 (Fig. 4) in the creel frame at points between the sprocket wheels.

A guide plate 16 is secured to the upper end of each bar 3 to extend in a vertical plane, the lower edge of said plate being arranged to move in close proximity to the inner edge of the track 9 and the upper edge of said plate 16 being arranged to travel in close proximity to the outer side of a guide flange 17 fixed in the creel frame. It will be seen that the series of plates 16 serve to prevent the upper chain 10 from moving out of a substantially straight line between the sprockets 12 and 13 and between the sprockets 13 and 14 and between the sprockets 14 and 12. The plates 16 also prevent the bars 3 from swaying on the chains and thus hold the yarn-mass supports 5 stationary during warping. That portion of the inner edge of the track 9 which is adjacent to the sprocket 13 is curved upon the arc of a circle concentric with the axis of said sprocket wheel, as shown at 18, and is similarly curved at 19. The plates 16 coact with these curved edges 18 and 19 to hold the bars 3 under control while traveling past the sprocket wheels.

Means is provided for driving the shaft 12^a to cause the series of yarn-mass supports to travel in a circuit. The means herein shown for this purpose comprises an electric motor 20 (Fig. 1) having on its armature shaft a pulley 21 from which power is communicated through a belt 22 to a pulley 23 fixed upon a shaft 24. On each end of the shaft 24 is fixed a bevel gear 25 that meshes with a bevel gear 26 that is fixed to one of the sprocket wheels 12. Any desired or conventional means may be provided for starting and stopping the motor and for running it at the desired speed.

At the outer side of each of the creel frames 1 and 2 is located means for guiding the yarn from the cheeses to the warper. If desired, means may be associated with the yarn-guiding means for detecting exhaustion, breakage or ex-

cessive slackness of the yarn. The means herein shown for this purpose consists of vertical tiers or columns of yarn-guiding and detector units 27 similar to those described in my Patent No. 5 1,790,318, dated January 27, 1931, to which reference may be made for a full disclosure. The spacing of the columns of yarn-guiding units corresponds to the spacing of the bars 3, there being one unit in axial alinement with each 10 cheese which is in running position.

The mode of operation is as follows: Assume that those bars 3 which are positioned at the outer side of the creel frames 1 and 2 are provided with yarn masses, the yarns of which are 15 guided to extend to the warper. While those yarn masses are being unwound, the operative places yarn masses upon all of the other bars. When the yarn masses at the outer sides of the creel have been unwound completely or to the 20 desired extent and have been disconnected from the warper, the operative operates the motor 20 to cause the series of yarn-mass supports to move in the direction indicated by the arrows in Fig. 1, whereby yarn-mass supports carrying 25 full cheeses are brought to the outer side of the creel and the yarn-mass supports with the emptied or substantially empty cores are brought to the inner side of the creel. When the full cheeses have been brought into approximately 30 unwinding position, the operative runs the motor intermittently so as to inch the series along until the full cheeses are in axial alinement with their respective yarn guides. The yarns of the 35 full cheeses are then connected to the warper and warping resumed, after which the operative proceeds to remove the empty cheese cores and substitute full cheeses.

It will be seen that the construction herein disclosed greatly facilitates the reloading of the 40 yarn-mass supports, that the time required to replace (in unwinding position) unwound cheese cores with full cheeses is reduced to a minimum, and that the operation of bringing full cheeses into unwinding position requires no appreciable 45 physical exertion on the part of the operative, as all that is required is the operation of the electric motor 20. It thus becomes possible to reduce to a minimum the time the warper is idle.

50 I claim as my invention:

1. A creel comprising a framework, an endless track in the upper portion of said framework, an endless series of yarn-mass carriers, each carrier having a roller arranged to run upon said 55 track, a flexible element connecting said carriers together in spaced relation, means for supporting and driving said flexible element, a series of yarn guides located along a portion of the circuit through which said carriers are arranged 60 to travel, a member connected to each carrier, and a guide arranged to be engaged by said members to retain said rollers on said track at points between the flexible-element-driving means and to prevent said carriers from swaying with reference to said yarn guides.

65 2. A creel comprising a framework, an endless track in the upper portion of said framework, an endless series of vertically elongated yarn-mass carriers, each carrier having at its upper end 70 a roller arranged to run upon said track, a flexible element connecting the upper ends of said carriers together in spaced relation, means for supporting and driving said flexible element, a member connected to the upper end of each carrier, and a guide arranged to be engaged by said

members to retain said rollers on said track at points between the flexible-element-driving means and to prevent said carriers from swaying with reference to said flexible element.

3. A warper creel comprising a V-shaped 5 framework, stationary yarn guides at the outer sides of said framework, and two endless series 10 of yarn-mass supports mounted in said framework each arranged to travel in a circuit along an outer side of the latter and the corresponding inner side, and means for simultaneously driving said series of supports whereby to position yarn masses in operative relation to the yarn guides for unwinding, and to position yarn-mass supports at the inner sides of the framework 15 for loading.

4. A warper creel comprising a framework, a stationary series of yarn guides at the outer side of said framework, and an endless series of 20 yarn-mass supports mounted in said framework to travel along the inner and outer sides of the latter, whereby to position yarn masses in operative position behind the yarn guides for unwinding, and to position yarn-mass supports at the inner side of the framework for loading. 25

5. A warper creel comprising a framework, an endless series of yarn-mass supports mounted in said framework to travel in a circuit, a stationary series of yarn guides adjacent to a part of 30 said circuit, and means to cause the series of yarn-mass supports to travel, whereby to position yarn masses in operative relation to the yarn guides for unwinding, and to position yarn-mass supports at other portions of the circuit for loading.

6. A creel comprising two endless chains arranged to move in parallel horizontal planes, bars extending vertically between and connecting said chains, and a plurality of yarn-mass supports upon and extending longitudinally of each bar. 40

7. A creel comprising two endless chains arranged to move in parallel planes, bars extending between and connecting said chains, a plurality of yarn-mass supports upon and extending longitudinally of each bar, and means for driving said chains. 45

8. A creel comprising a plurality of vertical bars, a plurality of yarn-mass supports upon and extending longitudinally of each bar, and means for causing said bars to travel in a circuit in definitely spaced relation to one another. 50

9. A creel comprising two endless chains arranged to move in parallel horizontal planes, a vertical series of yarn-mass supports connected to and extending between said chains, and a group of 55 yarn guides located alongside a portion of the path in which said series of supports is arranged to move, the yarn guides being spaced horizontally and vertically to correspond with the spacing of those yarn-mass supports which are adjacent to said group at any given time.

10. A creel comprising an endless series of vertical members arranged to move in a horizontal path, a vertical series of yarn-mass supports on each of said members, and a group of 65 yarn guides located alongside a portion of said path, the yarn guides being spaced horizontally and vertically to correspond with the spacing of those yarn-mass supports which are adjacent to said group at any given time. 70

11. A creel comprising an endless series of vertical members arranged to move in a horizontal path having an outer portion and an inner portion, a vertical series of yarn-mass supports on each of said members, a group of yarn guides 75

located along the outer portion of said path, the yarn guides being spaced horizontally and vertically to correspond with the spacing of those yarn-mass supports which are at the outer portion of said path at any given time, and means to move said series in said path to replace the last-mentioned yarn-mass supports with those which were at the inner portion of said path.

5 12. A creel comprising an endless series of vertical members arranged to travel in an endless horizontal path, a plurality of yarn-mass supports on each member, means for causing the series to travel in said path from one position to another, and means to prevent said members from swaying while in adjusted position.

10 13. A creel including a frame, a plurality of supply-holder carriers extending across the frame, endless conveyors connecting the ends of said carriers and mounted for travel on the 15 frame, and means for actuating the conveyors.

14. In a creel, the combination of a frame having opposite wings spaced apart to provide a charging station therebetween, endless conveyors travelable across the ends of the opposite wings of the frame, carriers extending laterally of each wing of the frame between the conveyors and connected to be traveled thereby, and a series of supply-holders carried by each carrier.

15 14. In a creel, the combination of an upright frame, chain-wheels journaled at either end of the frame adjacent the top and bottom thereof, endless chains extending between the wheels, carrier-rods attached at their ends to said chains to extend therebetween, supply-holders mounted in series along the carrier-rods, and means to operate the chain-wheels to travel the chains to shift the carrier-rods from one side of the frame to the other.

BURT A. PETERSON. 20
